His Attorney.

UNITED STATES PATENT OFFICE.

WILLIAM J. A. LONDON, OF SPRINGFIELD, MASSACHUSETTS, ASSIGNOR TO GENERAL ELECTRIC COMPANY, A CORPORATION OF NEW YORK,

ELASTIC-FLUID TURBINE.

Specification of Letters Patent. Patented June 4, 1918.

1,268,738.

Application filed September 13, 1917. Serial No. 191,147.

To all whom it may concern:

Be it known that I, WILLIAM J. A. LONDON, a subject of the King of Great Britain, residing at Springfield, in the county of 5 Hampden, State of Massachusetts, have invented certain new and useful Improvements in Elastic-Fluid Turbines, of which the following is a specification.

The present invention relates to elastic 10 fluid turbines of the type comprising a plurality of wheels mounted on a shaft with nozzle diaphragms, located between them to form stages, and particularly to such turbines where there is a single wheel per stage. 15 In connection with the construction of such turbines, it is desirable to form both the wheels and diaphragms of sheet material, as this gives a light compact structure, and one which is cheap to build. The stresses 20 set up in the hub of a turbine wheel are of considerable magnitude, and one of the difficulties heretofore experienced with sheet metal wheel structures has been to obtain a sufficiently strong and rigid connection between the wheels and the shaft. In such 25 turbine structures there is provided a packing between each diaphragm and the shaft, and, of course, the amount of leakage through these depends upon the packing 30 diameters, the greater the diameter the greater the leakage owing to the greater circumference through which leakage may occur.

The object of the present invention is to 35 provide an improved turbine structure wherein the wheel structures are rigidly connected to the shaft, and in which the packing diameters are reduced to a minimum to keep the leakage losses as low as 40 possible.

For a consideration of what I believe to be novel and my invention, attention is directed to the accompanying specification and the claims appended thereto.

45 In the drawing, the figure is a sectional view of a portion of a turbine illustrating my invention.

Referring to the drawing, 1 indicates a 50 turbine shaft and 2 the turbine casing. The turbine casing is divided into a number of stages by means of the nozzle diaphragms 3 which are built up of plates 4 and are spaced apart by flanges 5. 6 indicates the nozzle partitions. The detail structure of the nozzle diaphragms forms no part of

the present invention, and further description is accordingly considered unnecessary. Any suitable structure may be used. The diaphragm structure indicated in the present instance is described and claimed in the 60 application of myself and Edmund M. Phillips, Serial No. 206,728, filed Dec. 12, 1917. Located in each stage is a turbine wheel carrying a ring of blades 7. The wheel is formed of two plates of sheet material 8 and 9 provided with inturned flanges 10 at their peripheries which hold the buckets in place. The outer portion of the plates are held in spaced relation to each other at their peripheries by suitable spacing members 11 through which extend rivets 12. Adjacent the shaft the plates 8 and 9 are in contact with each other, as indicated at 13, and are provided with shoulders 14 and flanges 15 which form annular recesses 75 16 for the reception of holding rings 17 which are forced over the flanges 15 and are riveted to each other as indicated at 18. According to my invention I tie the wheel hubs of adjacent stages together in pairs 80 by means of an intermediate ring 19 formed integral with the adjacent holding rings 17. The rings 19 make a tight fit with the shaft 1 and are also keyed to the shaft along with the adjacent wheels on each side 85 thereof by a key 20. This gives a strong rigid hub structure which is firmly anchored to the shaft and is able to withstand the centrifugal stresses set up therein. Each 90 diaphragm carries a packing 21 of suitable structure to prevent leakage as far as possible between the diaphragm and the rotor. A well known form of packing is shown provided with the usual garter spring 22 for holding it yieldingly in position. It 95 will be noted that the packing members 21 between turbine wheels which are tied together by intermediate rings 19 pack against such rings, while the others pack directly against the shaft. The average 100 packing diameter is the mean between these two. The utilization of the intermediate rings 19 to tie the wheels together in pairs does not, therefore, greatly increase the average packing diameter over the diameter 105 of the shaft.

In accordance with the provisions of the patent statutes, I have described the principle of operation of my invention, together with the apparatus which I now consider to 110

represent the best embodiment thereof; but I desire to have it understood that the apparatus shown is only illustrative and that the invention can be carried out by other means.

What I claim as new and desire to secure by Letters Patent of the United States, is:

1. In an elastic fluid turbine, the combination of a shaft, wheels having flanges which engage the shaft, holding rings for said flanges, and an intermediate ring between some of the wheels which engages the shaft and is formed integral with the adjacent holding rings.
- 10 2. In an elastic fluid turbine, the combination of a casing, a shaft, diaphragms in the casing which divide it into stages, wheels in said stages, said wheels having flanges which engage the shaft and holding rings surrounding the flanges, intermediate rings between some of said wheels which engage the shaft and are connected to the adjacent holding rings, and packing members for the diaphragm which pack against said intermediate rings and the shaft.
- 15 3. In an elastic fluid turbine, the combination of a casing, a shaft, diaphragms in the casing which divide it into stages, wheels in said stages, each of said wheels being formed of a pair of plates of sheet material, each of which has a flange which engages the shaft, holding rings surrounding said flanges, intermediate rings in every other space between the opposing faces of adjacent wheels, which rings engage the shaft and are connected to the adjacent holding rings, and packing members for the diaphragms which pack against said intermediate rings and the shaft.
- 20 4. In an elastic fluid turbine, the combination of a shaft, wheels formed of plates of sheet material fastened together and provided with flanges which engage the shaft, and rings which surround the shaft in every other space between the opposing faces of adjacent wheels and are connected to adjacent wheels to tie them together in pairs.
- 25

In witness whereof, I have hereunto set my hand this tenth day of September, 1917.

WILLIAM J. A. LONDON.
